UNITED STATES PATENT OFFICE.

HENRY ROTH, OF TWO RIVERS, WISCONSIN.

FLUE CLEANER.

Application filed February 14, 1925. Serial No. 9,236.

To all whom it may concern:

Be it known that I, HENRY ROTH, a citizen of the United States, residing at Two Rivers, in the county of Manitowoc 5 and State of Wisconsin, have invented certain new and useful Improvements in Flue Cleaners, of which the following is a specification.

This invention relates to flue cleaners, 10 and has for its object to provide, in a manner as hereinafter set forth, a device of the class referred to with means whereby the clogging of the soot, dislodged from the walls of the flue during the cleaning operation, in the cleaner is prevented.

A further object of the invention is to provide, in a manner as hereinafter set forth, a device of the class referred to, with a plurality of sets of scraping members, 20 and with each set arranged in a polygonal-shaped group whereby the outer ends of the members of the group at each outer side of the latter will be arranged in horizontal alignment and so disposed, that each outer 25 side of the group will extend at right angles to an adjacent outer side thereby providing a series of right angularly disposed straight working edges to provide for the operation simultaneously upon a greater 30 area of the flue wall than that obtained by the circular or cylindrical form of flue cleaner, and under such conditions facilitating the cleaning operation.

A further object of the invention is to 35 provide, in a manner as hereinafter set forth, a device of the class referred to with a plurality of spaced sets of scraping members and means whereby the space between the sets can be adjusted to various widths 40 to prevent any possibility of the clogging of the soot to any extent within the device, and further with means whereby the length of the device can be lengthened or shortened when occasion requires.

Further objects of the invention are to 45 provide, in a manner as hereinafter set forth, a flue cleaner which is simple in its construction and arrangement, strong, durable, compact, adjustable, thoroughly 50 efficient and convenient in its use, readily assembled and comparatively inexpensive to manufacture.

With the foregoing and other objects in view, the invention consists of the novel 55 construction, combination and arrangement of parts as hereinafter more specifically de-

scribed and illustrated in the accompanying drawing, wherein is shown an embodiment of the invention, but it is to be understood that changes, variations and modifications 60 can be had which will fall within the scope of the claims hereunto appended.

In the drawing wherein like reference characters denote corresponding parts throughout the several views:—

Figure 1 is a vertical sectional view of a flue cleaner in accordance with this invention.

Figure 2 is a section plan illustrating the polygonal-shaped group arrangement of 70 a set of scraping members.

Figure 3 is a fragmentary sectional view.

Referring to the drawings, the cleaner includes a sectional body portion of cylindrical contour, referred to generally by the reference character 1, and which consists of upper, lower and intermediate clamping disks 2, 3 and 4, respectively, upper, lower and intermediate scraping member group holding disks 5, 6, and 7, respectively, and a series of spacing disks, as shown, seven in number and indicated at 8, 9, 10, 11, 12, 13 and 14. The number of spacing disks can be increased or decreased if desired. The disk 2 cooperates with the disk 5, the disk 3 with the disk 6 and the disk 4 with the disk 7 to clamp a set of scraping members to the body portion. Each of the disks of the body portion 1 is formed with a centrally disposed opening 15 for a purpose to be hereinafter set forth.

Arranged centrally of the body portion 1 is a clamping means for detachably securing the disks rigidly together and said means comprises an eye bolt consisting of a substantially elongated shank 16 formed at its upper end with an enlarged eye 17 and having its lower portion threaded as at 18. The shank 16 extends through the openings 15 and projects from the disk 3. The eye 17 extends above the disk 2 and interposed between the latter and the eye 17 is a washer 19 through which the shank 16 projects. Mounted on the lower end of the shank 16 is a washer 20 which abuts against the disk 3 and bearing on the washer 20 is a clamping nut 21 carried by the threaded portion 18 of the shank 16. A reciprocating element for the device is attached to the eye 17 and indicated at 17'.

A pair of removable hold-fast devices 22 are employed for securing the disks 2 and

5 together, and a pair of removable hold-fast devices 23 are employed for securing the disks 3 and 6 together.

The disk 5, has its upper face at the marginal portion thereof formed throughout with a series of radially extending grooves 24, the outer end of each terminates at the outer edge of the disk and the inner end thereof opens into a downwardly extending vertical socket 25.

The disk 7, has its upper face at the marginal portion thereof, formed throughout with a series of radially extending grooves 26, arranged out of alignment with respect 15 to the grooves 24 in the disk 5. The outer end of each of the grooves 26 terminates at the outer edge of the disk 7 and the inner end thereof opens into a downwardly extending vertical socket 27.

20 The disk 6, has its lower face at the marginal portion thereof formed throughout with a series of radially extending grooves 28, arranged out of alignment with respect to the grooves 24, 26. The outer end of 25 each of the grooves 28 terminates at the outer edge of the disk 6 and the inner end thereof opens into an upwardly extending vertical socket 29.

Carried by the body portion 1, is an upper, 30 an intermediate and a lower set of scraping members referred to generally by the reference characters 30, 31 and 32, respectively. Each set is in the form of a polygonal-shaped group, whereby the outer ends of the 35 members of the group at each outer side of the latter will be arranged in horizontal alignment and so disposed, that each outer side of the group will extend at right angles to an adjacent outer side thereby providing 40 a series of right angularly disposed straight working edges whereby each working edge will act throughout during the operation of scraping, that is to say all of the scraping members forming a working edge will be 45 active.

Each of the scraping members of each set is formed from a substantial length of wire of the desired rigidity provided with an inner right angularly disposed inner terminal portion. The wires forming the scraping members of the sets 30, 31 and 32 are indicated at 33, 34 and 35, respectively, and the angular end of each wire 33, 34 and 35, is indicated at 36, 37 and 38 respectively.

50 The wires 33 are mounted in the grooves 24 and the angular ends 36 thereof in the sockets 25. The wires 34 are positioned in the grooves 26 and the angular ends 37 thereof in the sockets 27, and the wires 35 are 55 mounted in the grooves 28 and the angular ends thereof in the sockets 29.

Each set of sockets 25, 27 and 29 is arranged in a circular row and the wires of each set 30, 31, 32 are of such length relatively to each other to provide for the align-

ing of the outer ends thereof at each side of a group. The outer ends of each set of wires at each outer side of a group are so shaped whereby the end edges thereof will extend in the same plane.

70 The disk 2 clamps the wires 33 to the disk 5. The disk 4 clamps the wires 34 to the disk 7 and the disk 3 clamps wires 35 to the disk 6. The wires 33, 34 and 35 project the desired distance from the disks 5, 6 and 7. 75 The wires at each side of a group gradually decrease in length from the center wire towards each end wire of a side.

The set 30 is arranged a substantial distance from the set 31, and the latter is arranged a greater distance from the set 32 than from the set 30, and by spacing the sets in such manner the clogging of the soot, dislodged from the walls of the flue during the cleansing operation, between the sets 30, 80 31 and 32 is prevented.

85 The body portion 1 can be lengthened or shortened by adding thereto or removing therefrom one or more spacing disks. The space between the sets 30, 31 can be increased 90 by the interposition of one or more spacing disks, and the space between the sets 31, 32 can be increased or diminished by the adding between or removing from one or more 95 of the spacing disks between the disks 6 and 7.

100 It is thought that the many advantages of a flue cleaner, in accordance with this invention, can be readily understood, and although the preferred embodiment of the invention is as illustrated and described, yet it is to be understood that changes in the details of construction can be had which fall within the scope of the invention as claimed.

105 What I claim is:—

110 1. A flue cleaner comprising an upper, a lower and an intermediate scraper member group holder disk, a clamping disk abutting each of said holder disks, spacing means between said intermediate and lower disks, a set of scraper members projecting from each of said holder disks and arranged in a polygonal-shaped group having horizontally disposed outer scraping sides, one disposed at right angles to the other, and means for detachably clamping said disks together to secure said sets in position.

115 2. A flue cleaner comprising an upper, a lower and an intermediate scraper member group holder disk, a clamping disk abutting each of said holder disks, spacing means between said intermediate and lower disks, a set of scraper members projecting from each of said holder disks and arranged in a polygonal-shaped group having horizontally disposed outer scraping sides, one disposed at right angles to the other, means for detachably clamping said disks together to secure said sets in position, said lower set spaced a greater distance from the interme- 120 125 130

diate set than the upper set from the latter.

3. A flue cleaner comprising a plurality of spaced scraper member holder disks, a clamping disk abutting each holder disk, a set of scraper members projecting from each holder disk and arranged in a polygonal-shaped group having horizontally disposed outer scraping sides, one disposed at right angles to the other, and means for detachably clamping said disks together to secure said sets in position.

4. A flue cleaner comprising a plurality of spaced scraper member holder disks, a clamping disk abutting each holder disk, a set of scraper members projecting from each holder disk and arranged in a polygonal-shaped group having horizontally disposed outer scraping sides, one disposed at right angles to the other, means for detachably clamping said disks together to secure said

sets in position, each of said holder disks having the marginal portion of one face formed throughout with a series of radial grooves each opening at its inner end in a vertical socket, and said scraping members 25 mounted in said grooves and sockets.

5. A flue cleaner comprising a plurality of spaced scraper member holder disks, a clamping disk abutting each holder disk, a set of scraper members projecting from each 30 holder disk and arranged in a polygonal-shaped group having horizontally disposed outer scraping sides, one disposed at right angles to the other, means for detachably clamping said disks together to secure said sets in position, said lower set spaced a greater distance from the intermediate set than the upper set from the latter.

In testimony whereof, I affix my signature.

HENRY ROTH.
